UNITED STATES PATENT OFFICE.

SIDNEY A. KELLER, OF NEW YORK, N. Y., ASSIGNOR TO MARCUS T. GOLDSMITH, OF NEW YORK, N. Y.

DESIGN FOR A BAG-FRAME.

SPECIFICATION forming part of Design No. 35,465, dated December 24, 1901.

Application filed September 21, 1901. Serial No. 76,079. Term of patent 3½ years.

To all whom it may concern:

Be it known that I, SIDNEY A. KELLER, a citizen of the United States, and a resident of New York, in the county of New York and State of New York, have invented and produced a certain new and useful Design for Bag-Frames, of which the following is a specification.

In the accompanying drawing, to which reference is made and which forms a part of this specification, the figure illustrates a bag-frame in accordance with my design.

The leading feature of my design consists of a three-scalloped lower edge, an opposite curved central dome, and a curve at each side of the said central dome, each of which join the outer curve of the lower edge and of the ornamentation, as shown and described.

In the drawing, 2 3 4 5 designate the curves or scallops of the lower edge, 6 the opposite curved central curve or dome, and 7 7 the curves each side of the said central curve or dome. The curves 7 7 join the curves 5 5 and

form points 8 8. Deep depressions 9 9 appear between the central dome 6 and the side curves 7 7, and a plain girder 10 bounds the edges of the dome 6 and side curves 7 7. The space within and beneath the said central dome 6 is ornamented with a face crowned with leaves and flowers, and it is supplied with mustache and whiskers, the former streaming forth beneath the curves 7 7. Beneath one of the curves 7 appears the figure of cupid in back pose, holding with one hand the mustache of the central figure, while beneath the other curve 7 appears the figure of cupid in front pose, holding with one hand the mustache of the central figure, all as shown.

What I claim is—

The design for a bag-frame, substantially as herein shown and described.

SIDNEY A. KELLER.
